SPRAY AND JET NOZZLE

Clarence F. Dinley, Detroit, Mich., assignor, by
mesne assignments, to Solvent Machine Com-
pany, trustee, Detroit, Mich., a corporation of
Michigan

Application May 5, 1937, Serial No. 140,816

5 Claims. (Cl. 299—154)

My invention relates to spray-jet nozzles and the like, and particularly to the production of a flat spray or jet. An important object of the invention is to provide for spraying liquids containing fine solid particles or dirt for long periods without objectionable clogging of the spraying opening by the solid matter.

My new nozzle is especially adaptable and advantageous for spraying (hot) liquid cleaning agents, including grease solvents (e. g., chlorinated solvents, such as trichlorethylene, for instance) for the purpose of cleaning metal parts of adherent grease and solid particles of dirt, such as abrasive, buffing, and polishing agents. For this purpose, it is desirable to circulate and recirculate the solvent continuously for considerable lengths of time, during which the liquid solvent becomes charged with fine solid particles in suspension. These particles tend to clog up the spray devices or nozzles, compelling frequent costly shut-downs of the cleaning apparatus to allow of cleaning the nozzles; or, to minimize the frequency of such shut-downs, it is necessary to replace or purify the solvent oftener than would be required to keep it in effective dirt-removing condition. This is expensive, and generally entails a shut-down of the apparatus.

There is no great difficulty in spraying mere liquid, even when of rather thick consistency; and many types of nozzles heretofore used answer that purpose satisfactorily. But to spray in a flat sheet a liquid containing solid particles is much more difficult, if clogging up and virtual stoppage of the nozzle is to be avoided. One form of nozzle heretofore used for spraying liquids in a sheet consists of a flattened head widely spread out, with a mouth slit "from ear to ear" of this head, so to speak; but when the liquid contains solid particles, they gradually deposit in the outer sides of the head, where the velocity of the fluid is reduced, and the deposits grow inward toward the center. Another old form of nozzle consists of a tube with its end closed off something like a derby hat, with a diametrical slit across the end wall; but in this device, the solid particles deposit in the "dead" corners at either side of the slit, and gradually build and come together. Yet another form of nozzle is like a tube with the end flattened to a sort of slit, but nearly closed in the middle to spread the liquid out to each side: in this nozzle, the solid particles deposit in the center, where the velocity and flow are reduced.

My new nozzle operates without objectionable clogging many times as long as any nozzle here-
55 tofore available in the market. The distinctively

novel features of my nozzle that obviate clogging can best be explained by reference to a specific form of embodiment such as shown in the accompanying drawings, in which:

Fig. I is a tilted or perspective view of one 5 form of nozzle advantageously embodying my invention, showing the outlines of the flat spray of liquid that it produces.

Fig. II is a side or edge view of the same nozzle.

Fig. III is a plan view of the same nozzle, with 10 one side partly cut and broken away; and

Fig. IV is a front end view.

Fig. V is a side view of a cylindrical tubular blank suitable for the manufacture of the nozzle shown in Figs. I—IV; and

15

Fig. VI is an end view of this blank.

Figs. VII and VIII are similar views illustrating a stage in the manufacture of a nozzle from such a blank.

As shown in Figs. I, II, III, and IV, the nozzle has a round body portion 10, with cylindrical bore, and is externally screw-threaded on its inlet end 11 for convenience in attaching it to a liquid supply connection, Fig. I. The body portion 10 may be of any length that is desirable in a particular case, but is here shown quite short. At its discharge end or mouth 12, Fig. II, the nozzle is flat (Figs. I and IV), and has an elongated outlet orifice or slot opening 13 of uniform width. The connecting portion 14 between the body 10 and the mouth edge 12a which defines the outlet orifice 13 forms an easy, smooth transition from the round form to the flat. As shown in Figs. I and II, this transitional portion 14 is flattened more and more on its top and bottom sides, from the body 10 to the mouth 12, on a gradual, even taper, and is correspondingly widened out more and more horizontally. In other words, the internal passage in the portion 14 is defined by a surface which changes and merges continuously and substantially uniformly from the round inlet configuration at 10 to the elongated outlet orifice 13, and which terminates at the forward mouth edges 12a, which as here shown are perfectly straight. As here shown, all the longitudinal 40 elements of the internal surface of the portion 14 are approximately or substantially straight lines. In the flattened mouth portion 12, the edges of the nozzle are notched or slotted back at 15, in relieving prolongation or extension of the end slot opening 13, a distance between one and two times the width of the slot,—as here shown, about one and one-half times the width. In other words, the extremities of the elongated outlet orifice 13 are prolonged and extended back 50

45

55

55

at 15 from the edges 12a into the narrow sides 16 of the mouth 12. Preferably, also, as here shown, the corners of the flat mouth 12 are bevelled off at 16, in the general direction of the nozzle length. As best shown in Figs. I and II, the upper and lower corners of the slot opening 13 itself are also slightly relieved at 17, in the way of beveling or rounding.

From a consideration of Figs. I-IV in connection with the foregoing description, it will be seen that the interior of the nozzle presents no recesses or corners that may form dead places where the flow of the fluid is checked, or its velocity reduced. On the contrary, the fluid 10 sweeps through in a steady flow, which increases in velocity with the progressive flattening out in cross-section and the corresponding gradual reduction in internal cross-sectional area. The fluid remains under pressure and its velocity 15 builds up right to the very mouth opening, where the pressure is suddenly released.

In a nozzle through which the fluid sweeps freely at continually increasing velocity, as above described, the relief or cutting back at 15 in the 20 edges of the mouth has a peculiar action, serving to augment the flow in the edges of the flat nozzle passage behind these notches, rather than to spread or fan out the flat liquid spray or jet beyond the nozzle opening 13. This compensates 25 for the extra retarding friction of the fluid with the edges of the internal nozzle passage. The bulk of the fluid sweeps through and out under the impetus of the velocity previously gained in the nozzle passage, with only a little more lateral 30 spread than would be produced by the divergence of the nozzle edges as shown in Fig. III even in the absence of any notches 15. Thus the tendency toward deposition of solid particles at the 35 corners or extremities of the orifice 13 is so materially reduced that my nozzle with the notches 15 will operate without clogging objectionably several times as long as if the corners of the mouth 40 were not thus relieved. The relief of the edge corners at 17 has a similarly helpful effect, though 45 less marked.

Figs. V-VIII illustrate a preferred method of making a nozzle such as shown in Figs. I-IV. Starting with a suitable length of cylindrical metal tubing as a blank, as shown in Figs. V and 50 VI, the first step is to mash it down on a taper, thus flattening the mouth end 12 and forming a uniform mouth slot 13 as shown in Figs. I-IV. This may be done conveniently between relatively 55 inclined flat die surfaces, as well understood in metal working. The next step is to cut off the corners of the flattened end 12 on a flat bevel 16, as indicated in dot-and-dash lines in Figs. VII

and VIII, thereby forming the notches 15 as shown in Figs. I-IV. This may conveniently be done by milling or grinding. The beveling method of producing the notches 15 has the advantage of leaving these notches with edges of 5 almost knife-edge sharpness at their bottoms, so that there is no drag on the escaping fluid at these points, to facilitate formation of deposits there, and no surface to receive such deposits. If found desirable, of course, the mouth slot 13 10 may be internally finished and the bottoms of the notches 15 squared by filing, or by an operation with a milling cutter, or by grinding.

The incidental operations of threading the blank or nozzle as at 11 in Figs. II and III and 15 beveling or rounding off the corners of the slot opening 13 at 17 may be done in any preferred sequential relation to the other operations, by methods well known in metal working.

Having thus described my invention, I claim: 20

1. A flat-spray nozzle having an inlet round in cross-section and a narrowed outlet or mouth with an outlet orifice of elongated shape and uniform width, and having a passage connecting said inlet to said outlet orifice and defined by a 25 surface which changes and merges continuously and uniformly from the round configuration of the inlet to the elongated outlet orifice, and terminates at the forward mouth edge which defines said outlet orifice, the extremities of the elongated outlet orifice being prolonged and extending back from its said edge into the narrow sides of the mouth; all so that the fluid sweeps right through the nozzle and its mouth under pressure, while internal corners and relatively dead places 30 within the nozzle are avoided, as well as frictional drag at the edges of the flat fluid stream.

2. A flat-spray nozzle as set forth in claim 1 having the forward mouth edge which defines the elongated outlet orifice slightly relieved.

3. A flat-spray nozzle as set forth in claim 1 wherein the mouth edges which define the outlet orifice are straight.

4. A flat-spray nozzle as set forth in claim 1 having the corners of its narrowed mouth excised 45 in the general direction of the nozzle length, so that the prolongations of the outlet orifice back into the narrow sides of the mouth terminate in knife edges at their bottoms.

5. A flat-spray nozzle as set forth in claim 1 50 consisting of a length of originally round tubing having its end portion flattened on a substantially even taper and the corners of its narrowed mouth excised in the general direction of the nozzle length, so as to prolong the outlet orifice 55 back into the narrow sides of the mouth.

CLARENCE F. DINLEY.
